UNITED STATES PATENT OFFICE.

STEPHEN KEMP, OF NORTH BRIXTON, ENGLAND.

BOTTLE-STOPPER.

SPECIFICATION forming part of Letters Patent No. 711,869, dated October 21, 1902.

Application filed August 25, 1902. Serial No. 120,963. (No model.)

To all whom it may concern:

Be it known that I, STEPHEN KEMP, inventor and model-maker, a subject of the King of Great Britain, residing at 106 Cowley road, 5 North Brixton, in the county of Surrey, England, have invented certain new and useful Improvements in Stoppers or Means for Preventing the Refilling of Bottles and the Like, of which the following is a specification.

10 This invention relates to stoppering bottles and other such like vessels, and is designed to produce what are known as "non-refillable" bottles, so as to make them inviolable and render it impossible to tamper with the contents while in such bottles, and primarily has for its object to prevent refilling bottles and other similar vessels with spurious concoctions and passing them off as the original liquid material indicated by the marking on 15 the bottle itself or by the label or other mark on said bottle. This stopper once inserted in the neck of the bottle cannot be removed without violence sufficient to break the bottle and make the attempt obvious to any 20 server. The contents of the bottle will only flow when the bottle is held in certain positions, whereupon the contents, or as much as may be required thereof, can be withdrawn, while the refilling of the bottle is absolutely 25 prevented, all as hereinafter described with reference to the accompanying drawings.

Referring to the drawings, Figure 1 is a view in side elevation of a stopper constructed according to the present invention. Fig. 2 is a 30 plan of the top end of the stopper. Fig. 3 is a plan of the bottom end of the stopper. Fig. 4 is a vertical sectional view on line 4-4, Fig. 1, showing the stopper in the neck of a bottle and with the valve locked against the valve-seat- 35 ing, so as to hermetically close the bottle, the cone *j* being shown, however, in elevation. Fig. 5 is a cross-sectional view on line 5-5, Fig. 4. Fig. 6 is a similar view to Fig. 4, showing the valve unlocked, so as to enable 40 the contents of the bottle to be poured out. Fig. 7 is a vertical cross-sectional view at right angles to Fig. 6. Fig. 8 shows the stopper when the bottle is held in position to pour out the contents. Fig. 9 is a side view in elevation, partly in section, of a slightly-modified arrangement of the air and liquor tubes, 45 Fig. 10 being an under side plan thereof.

The neck *A* of the bottle or other receptacle to be stoppered according to this invention is provided with a series of (say two or 5 more) recesses *B* inside the neck of the bottle a short distance below the top of such neck *A*, or, if desired, an internal circumferential groove may be used instead of said recesses *B*. A piece of cork or any other suitable elastic material *a* is located centrally below a metal disk *b*, to which latter said cork *a* may or may not be attached, as desired, said cork *a* being adapted to enter the neck *A* of the bottle and fit same tightly. 60 This disk *b*, which I will term the "platform," is advantageously of the same diameter, or thereabout, as the outside of the neck *A*, (see Fig. 4, &c.,) and for the purpose of permanently securing the stopper in the bottle-neck 65 two or more spring clips or hooks are provided, (see Figs. 1 and 7,) each "clip" consisting of a thin metal strip *c*, which at its upper end is permanently attached to the platform *b*, and at its lower end each strip *c* is 70 provided with an exterior projection or hook *d* to engage in the said recess or inset *B* inside the bottle-neck, the formation and action of these clips *c* and *d* being such that when the cork part *a* of the stopper is driven into 75 position in the neck *A* the clips *c* *d* will be forced down the neck of the bottle therewith, the elasticity of the cork allowing the clips to be pressed inwardly into the cork *a* until 80 said hooks or projections *d* come opposite the recesses *B*, (or below the top edge of the circumferential groove, if the latter be used,) whereupon the resilience of the cork will force 85 outward the projection *d* into said recess, (or groove,) and thereby the stopper will be 90 securely and immovably locked in position in the neck of the bottle, (see Fig. 7,) or this stopper may be mounted and immovably secured in the bottle-neck in any other desired 95 and suitable manner.

Through the cork *a* two tubes *e* and *f* pass from the bottom of the cork up to and through the platform *b*, and advantageously each tube projects slightly above the platform *b* for forming a valve-seat. These two tubes *e* and *f* are of different sizes, the larger one, *e*, being the liquor-duct and the smaller one, *f*, being the air-duct, and to prevent said tubes contaminating or otherwise affecting the contents 100

of the bottle said tubes *e* and *f* are preferably made of glass or china, and, furthermore, in order to protect such glass or china tubes from breakage the upper part of same may be in-
5 cased in a thin metal tube *x* or other protecting-sheath inserted from the upper part of the cork *a* downward, but always in such wise that the liquor cannot reach such metal tube or protecting-sheath.

10 In practice it has been found advantageous to have the air-tube *f* prolonged or extended for, say, an inch, more or less, below the bottom end of the cork *a*, while the liquor-tube *e* may advantageously terminate flush, or there-
15 about, with the bottom of said cork *a*.

On the upper side of the platform *b* is hinged at *b'* the flap-valve or "clapper" *g*, which on its upper side and opposite, or thereabout, to the hinge *b'* is provided with the cam-surface 20 or outwardly-extending curved edge *g'*, as and for the purposes hereinafter described, while the under side of said flap-valve *g* is or may advantageously be provided with any suitable pad *g*² (see Fig. 7) or packing or lining to insure a close fit of said clapper or valve *g* on each of the tubes *e* and *f*, such pad, &c., *g*² being of any suitable more or less elastic material adapted to form a tight fit on the valve-seating and at same time of such a character as not to injuriously affect the contents of the bottle in any way.

h is the outer cap or exterior covering, the edges of which cap *h* fit over and extend below the platform *b* and also advantageously 30 extend a little below the mouth of the bottle, said cap *h* being held in position upon and with respect to the platform *b* (and so as to be capable of rotary movement with respect thereto) in any suitable manner. For instance, 35 said cap may be provided with an internal shoulder *h*^x a little way up inside the bottom edge of said cap *h*, which shoulder *h*^x rests upon or against the platform *b*, and then by inserting a ring or washer *i* below said platform and inside the lower edge of said cap *h* and there permanently securing said ring *i*— 40 for instance, by soldering said ring *i* to the cap or securing same together by pins or rivets—thereby the cap is prevented from being 45 removed off the platform, but is always mounted in such wise as to be capable of partial rotary movement with respect to said platform, suitable stops being provided to limit the rotary movement of such cap with respect 50 to said platform. Inside the top of said cap is rigidly fixed or formed the bell-mouth or inverted-cone-shaped device *j*, the edges of this latter extending down toward the flap- 55 valve, but always so as to leave sufficient clearance or space between same and the top 60 of the flap for a weighted ball or spherical body *k* (of glass or any other suitable material) to move loosely between said flap *g* and the inverted cone and so as to prevent said ball *k* from escaping from under said fixed cone *j*, the edge of such cone *j* being slightly

cut away at *j'* (see Fig. 8) to enable the upwardly-projecting edge or cam-surface *g'* on the flap-valve *g* to enter said recess *j'*, and thus enable the valve *g* to open sufficiently 70 (when in the position shown in Fig. 8) for pouring out the contents of the bottle.

Inside the upper part of the cap *h* is a fixed surface *h'* in such position as to be adapted to ride against the cam-surface *g'*, when the cap 75 is rotated into the position shown in Fig. 4, so as to thereby force the valve *g* tightly down upon its seating on the upper end of the tubes *e* and *f* and there lock and hold same, so as to thus hermetically close the bottle when 80 not required for use.

When it is desired to pour out the contents of the bottle, the cap *h* is rotated so as to move the surface *h'* clear of the cam *g'*, and thus unlock and leave the valve *g* free, and 85 on inclining the bottle into the position shown in Fig. 8 the ball *k* will pass farther up into the cone *j*, the flap-valve *g* will fall back and open the ducts *e* and *f*, and the liquid can then flow through the duct *e*, through the inside of the cap *h*, and pass out from the latter through the outlet *h*², while air can enter the bottle through the air-tube *f*. As the bottle is returned from the position shown in Fig. 8 (or other inverted position) back to the 90 normal upright position before the bottle reaches the horizontal the ball *k* by reason of the inverted cone *j* bears against the valve *g* and presses the latter toward and against its seating before the bottle has reached the 100 horizontal position, this operation of the ball *k* upon the clapper-valve *g* being a very important and essential feature of the present invention.

In Figs. 9 and 10 a slight modification is 105 shown—namely, instead of having the tubes *e* and *f* arranged through separate parts of the cork, as illustrated in Figs. 1 to 8, I may form, arrange, or mount the air-tube *f* inside the liquor-tube *e*. For instance, said air-tube 110 *f* may be formed by the division-wall *f'*, formed in or fused to the large glass liquor-tube *e*, a metal tube *x* or protecting-sheath for the tube *e* being provided in the cork *a*, as hereinbefore described with reference to 115 the separate tubes *e* and *f*.

Instead of using a single cam-surface *g'* on the clapper *g* two or more such cam-surfaces may be arranged on said clapper *g* and a corresponding number of fixed surfaces *h'* arranged on the inside of the cap *h* to engage with said cam-surfaces, and thereby force the clapper in an even manner down upon its valve-seating.

With stoppers constructed as hereinbefore 125 described and permanently secured in the neck of the bottle in any suitable manner it will be found impossible either to tamper with the contents of the bottle or when the contents of such bottle have been withdrawn 130 it will be equally impossible to force liquid into the interior of said bottle or otherwise

refill same without removing this stopper or breaking the bottle.

Having now described my invention, what I claim as new, and desire to secure by Letters 5 Patent of the United States, is—

1. The combination with a bottle-stopper having air and liquid ducts therethrough; of automatic means for opening and closing the outer ends of said ducts, a sealing-cap inclosing said automatic means, and means operated by said sealing-cap for opening and closing the outer ends of said ducts after the insertion of the stopper in the bottle.

2. The combination with a bottle-stopper having air and liquid ducts therethrough; of automatic means for opening and closing the outer ends of said ducts, a sealing-cap inclosing said automatic means, and means operated by said sealing-cap for locking and releasing the closing device over the outer ends of said ducts after the insertion of the stopper in the bottle.

3. The combination with a bottle-stopper having air and liquid ducts therethrough; of automatic means for opening and closing said ducts by tilting the bottle, comprising a valve adapted to seat on the outer end of said ducts, a loose ball adapted to rest on said valve, and an inverted-cup-shaped device adapted to retain said ball in position on top of the valve and to guide same against the valve when the bottle is tilted, and a sealing-cap inclosing said automatic means.

4. The combination with a bottle-stopper having air and liquid ducts therethrough and means for permanently retaining the stopper in the bottle; of automatic means for opening and closing the outer ends of said ducts comprising a valve adapted to seat on the outer end of said ducts a loose ball adapted to rest on said valve and an inverted-cup-shaped device adapted to retain said ball in position on top of the valve and to guide same against the valve when the bottle is tilted, a sealing-cap inclosing said automatic means and carrying the inverted-cup-shaped device on the inside of said sealing-cap and means operated by said sealing-cap for locking and releasing the closing device over the outer

ends of said ducts after the insertion of the 50 stopper in the bottle.

5. The combination with a bottle-stopper having air and liquid ducts therethrough and means for retaining the stopper in the bottle and preventing the removal of the stopper 55 without breaking the bottle; of automatic means for opening and closing the outer ends of said ducts comprising a valve adapted to seat on the outer end of said ducts a loose ball adapted to rest on said valve and an inverted-cup-shaped device adapted to retain said ball in position on top of the valve and to guide same against the valve when the bottle is tilted, a sealing-cap inclosing said automatic means and carrying the inverted- 60 cup-shaped device on the inside of said sealing-cap and means operated by the said sealing-cap for locking and releasing the closing device over the outer ends of said ducts after the insertion of the stopper in the bottle. 70

6. The combination with a bottle-stopper having air and liquid ducts therethrough; of automatic means for opening and closing the outer ends of said ducts, comprising a hinged plate, a valve on the under side of said plate 75 adapted to seat on said ducts, a platform on which said plate is hinged, air and liquid ducts supported on said platform, a cork stopper below said platform and attached thereto and surrounding said air and liquid 80 ducts, a loose ball on the outer side of said plate, a sealing-cap inclosing said automatic means for opening and closing said ducts, said sealing-cap being adapted to be rotated within certain limits, an inverted-cup-shaped 85 device carried on the inside of said sealing-cap and adapted to retain said ball in position on top of the plate and to guide same against the valve when the bottle is tilted and an opening through said sealing-cap for 90 the liquid to pass out.

In witness whereof I have hereunto set my hand in presence of two witnesses.

STEPHEN KEMP.
